Attorneys.

UNITED STATES PATENT OFFICE.

IVAR F. WARME, OF SYRACUSE, NEW YORK, ASSIGNOR TO CONTINENTAL CAN COMPANY, INCORPORATED, OF SYRACUSE, NEW YORK, A CORPORATION OF NEW YORK.

CAN-END CLENCHER.

1,329,259.

Specification of Letters Patent. Patented Jan. 27, 1920.

Application filed July 18, 1916. Serial No. 109,971.

To all whom it may concern:

Be it known that I, IVAR F. WARME, a citizen of the United States, residing at Syracuse, in the county of Onondaga, State of 5 New York, have invented certain new and useful Improvements in Can-End Clenchers, of which the following is a description, reference being had to the accompanying drawing and to the figures of reference marked 10 thereon.

The invention relates to new and useful improvements in machines for clenching the ends on cans, and more particularly to a machine wherein the can which has been previously filled is rounded up, a can end seated therein, and the curled edge of the can end turned underneath the flange of the body at opposed points so as to clench the can end firmly to the can body. 15 An object of the invention is to provide a machine of the above character wherein the can end is clenched to the can body by opposed devices which move tangentially of the can body while turning the curl of the can end underneath the flange of the can body. 20

Another object of the invention is to provide a machine of the above character wherein a can having been previously filled 25 is raised underneath a stack of can ends, rounded up, and the lowermost can end seated in the can, after which clenching devices operating at diametrically opposed points separate the lowermost can end from the stack and roll the curl of the can end underneath the flange of the can body for 30 clenching said can end to the can body. 35

A further object of the invention is to provide a device of the above character wherein 40 the clenching members are provided with a cam ledge for separating the lowermost can end from a stack of can ends, a curling groove for turning the curl of the can end underneath the flange of the can body, and 45 a releasing recess which permits the can bodies with the ends clenched thereto to be released while the stack is supported by said clenching members.

A still further object of the invention is 50 to provide a machine of the above character wherein a plurality of cans may have their ends clenched thereto simultaneously.

These and other objects will in part be obvious and will in part be hereinafter more 55 fully disclosed.

In the drawings, which show by way of illustration one embodiment of the invention:—

Figure 1 is a vertical sectional view through a gang machine embodying the improvements; 60

Fig. 2 is a plan view of the same;

Fig. 3 is a horizontal sectional view on the line 3—3 of Fig. 1;

Fig. 4 is an enlarged detail showing the 65 position of the can end and the stack before the can body has been moved relative to the stack for seating the can end in the can body;

Fig. 5 is a similar view, but showing the 70 can end clenched to the can body and separated from the stack;

Fig. 6 is a detail showing the position of the clenching members for releasing the can body with the clenched end thereon; 75

Fig. 7 is a bottom plan view of one of the clenching members;

Fig. 8 is a top plan view of the same;

Fig. 9 is a side view of the same;

Fig. 10 is a diagrammatic view, showing 80 the relative position of the curling groove and the separating cam to the can body and can end when the can end is seated in the can body; and

Fig. 11 is a similar view, but showing the 85 parts moved so as to curl the can end underneath the flange on the can body and so as to separate the stack from the can end.

The invention consists primarily in means for supporting the can and a stack holder, 90 which stack holder is mounted on a supporting plate having an opening therethrough which is tapered at its lower end to form a cone-shaped wall adapted to engage the can body as it passes through the opening, for 95 the purpose of rounding up the can body. Mounted to slide in the support for the stack on opposed sides of the opening are clenching members. Each clenching member is formed with a ledge on which the can 100 end rests before it is seated in the can body, and while on this ledge either the can body is raised or the stack with the support referred to lowered so as to cause the can end to be seated in the can body. After the can 105 end is seated in the can body, the clenching members are moved in a direction tangentially of the can bodies, a separating cam separates the lowermost can end from the stack, a curling groove engages the curled 110

edges of the can end and rolls the same underneath the flange of the can body, thereby clenching the can end to the can body, and a continued movement of these 5 clenching members brings recesses in a line with the can end and can body so that the can bodies with the clenched ends may be released while the stack is still supported by the clenching members. The clenching members are then withdrawn and the stack again drops onto the supporting ledge, placing another can end in position to be clenched to the next can body.

Referring more in detail to the drawings:—

There is shown more or less diagrammatically an apparatus or machine embodying the invention, said machine including a supporting base 1 having a plurality of recesses each of which receives a disk 2. These disks serve as supports for the filled can bodies which are indicated at C in Fig. 1 of the drawings. At each end of the supporting base there is a standard 3 which is rigidly secured to the supporting base. Mounted on these standards is a stack supporting member 4. As shown in the drawings, the machine is a gang machine, and there are four stacks, one for each can body. 20 These stacks, as above noted, are carried by this stack supporting member 4 which is formed with four openings 5 into which the stacked can ends drop by gravity. For the sake of clearness the stacked can ends have 25 been omitted in Fig. 1, but one stack is shown in Figs. 4 and 5.

The can ends are indicated at E. The openings 5 in the support are cylindrical in shape. At each side of the stack support 4 40 there is a recess 6. The support is also formed with openings 7 which lead from these recesses 6 into the openings 5. Mounted to slide in the recess 6 at one side of the stack support is a bar 8. The recess 45 is closed by a cover plate 9 which is secured to the support by screws 10. This bar 8 slides freely back and forth in the recess. At the other side of the machine there is a bar 11 which slides in the recess 6, and this 50 is held in place by a cap plate 12 secured to the support by screws 13. The bar 8 is formed with a rack 14, while the bar 11 is formed with a rack 15. These racks mesh with a gear 16 which is fast to a shaft 17, 55 and this shaft may be rotated in any desired way. The bars 8 and 11 are similar in construction, except that they are reversed, for the reason that, when the bar 8 is moving in one direction, the bar 11 is moving in the 60 other direction.

Each bar has projecting cams extending therefrom, cut-away sections forming a supporting ledge, a separating cam, a curling groove, and a releasing recess. The supporting ledge is indicated at 18. Said bar

is cut away at 19 so as to expose this ledge 18, and when the cut-away portion 19 is in register with the opening 5, the stacked can ends will drop onto the supporting ledge 18. This is the normal position of the machine. 70

The filled cans are placed on the supports 2 and the cans are either raised or the stack support with the stack is lowered so as to bring about a relative movement between 75 the can ends and the stack. The lower face of the opening 5 is tapered as at 20. This tapering of the opening forms a cone-shaped wall which will engage the upper edge of the can body and round up the 80 same when this relative movement between the stack and the can body occurs. A further movement of the can body will cause the can end to be seated in the can body. In Fig. 4 of the drawings, the can body is 85 shown as coming up through the opening to engage the can end resting on the supporting ledges 18 of the bars 8 and 11.

After the can end has been fully seated in the can body, then the flange of the can 90 body, indicated at f, will be raised to a point above the ledge 18. In line with the upper face of the ledge 18 is a curling groove 21. Directly above the curling groove and leading down to a point which is in a plane 95 passing between the lowermost can end and the can end directly above the same is a separating cam 22. When the bar 11 is moved in the direction of the arrow in Fig. 9, the curling groove 21 engaging the curl of the 100 can end will turn the edge of the can end underneath the flange of the can body at the point where said groove engages the can end. At the same time, the separating cam 22 passes between the can ends. 105

In Fig. 10 there is shown diagrammatically the position of the can end and the can body just as the curling groove is engaging the edge of the can end, while in Fig. 11 the edge of the can end has been rolled underneath the flange on the can body and the separating cam has separated the stack from the lowermost can end. The continued movement of the bar 11 brings the recess 23 into alignment with the can end, and this 115 recess is shaped so as to release the can end and the can body which is clenched thereto.

From the above description, it will be apparent that the can end is clenched to the 120 can body by a clenching member which moves tangentially of the can body, and that the clenching occurs at diametrically opposed points on the can end. This clenching member performs the double function of 125 clenching the can end to the can body and separating the stack from the lowermost can end, and serves as a support for the stack until the can end clenched to the can body is released from the machine. 130

In Fig. 1 of the drawings, springs 24 are shown interposed between the base 1 and the support for the stacks, and these springs normally carry the supports for the stack 5 and the stack carried thereby. Limiting nuts 25 determine the extent of upward movement caused by the springs 24. The can bodies, as noted above, are placed on the supports 2, and the stack support may be lowered by depressing the same which compresses the springs 24, and this seats the can end in the can body. A rotation of the shaft 17 moves the rack bar 11 in one direction and the rack bar 8 in the other direction, and this movement of these bars 15 operates to perform the clenching of the can ends to the can bodies at points diametrically opposite, as above explained. The continued movement of these bars 20 finally releases the can ends and the can bodies and when the bars are returned the stacks drop again on the supporting ledges therefor, positioning the other can ends for a new set of can bodies.

25 While a gang machine has been shown, it will be understood that a single machine may be used embodying the features described for clenching the can ends to the can bodies. It will also be understood that 30 mechanism which has been shown more or less diagrammatically for the purpose of illustrating the invention may be embodied in a full automatic machine timed to feed the filled cans underneath the stacks to 35 bring about a relative movement of the stack and the can bodies so as to seat the can end in the can body after which the clenching takes place.

It is obvious that minor changes in the 40 details of construction and the arrangement of parts may be made without departing from the spirit of the invention as set forth in the appended claims.

Having thus described the invention, 45 what is claimed as new is:—

1. The combination of means for supporting a can, means for placing a can end on said can, and opposed clenching members movable bodily tangentially of the can end 50 for engaging the curled edge of the can end and turning the same beneath the flange on the can body.

2. The combination of means for supporting a can underneath a stack of can ends, 55 means whereby the lowermost can end of the stack may be seated in the can, and opposed clenching members movable bodily tangentially of the can end for separating

the seated can end from the stack and for clenching said can end at diametrically opposed points to the can body. 60

3. The combination of means for supporting a can underneath a stack of can ends, means whereby the lowermost can end of the stack may be seated in the can, and reciprocating clenching members each including a curling groove for curling the edge of the can end underneath the flange of the can body, and a separating cam for lifting the stack from the can end that is being 70 clenched to the can body.

4. The combination of a can body support, a stack holder support having a vertical opening therethrough, the lower edge of which is tapered for engaging and rounding up a can body, opposed members slidable longitudinally of the stack holder support, said opposed members each having a supporting flange on which the stack of can ends rest until the can body is seated 80 on the can end, means for curling the edge of the can end underneath the flange on the can body, and means for separating the stack and lifting the same from the can end that is being clenched to the can body. 85

5. The combination of means for supporting a can, a stack holder support above said can holder support and having a vertical opening therethrough, the lower edge of said opening being tapered to round up 90 the can body, bars disposed on diametrically opposite sides of the opening and slidable on said stack holder support, each bar having a ledge for supporting the stack, a curling groove for curling the edge of the can 95 end underneath the flange on the can body, a separating cam for lifting the stack from the can end that is being clenched to the can body, and a releasing recess whereby the clenched can end may be released while the 100 stack is supported by said bars.

6. A gang can clenching machine including in combination means for supporting a plurality of cans, means for placing can ends on each can and opposed clenching 105 members movable bodily tangentially of the cans for simultaneously engaging the curled edges of the can ends and turning the same beneath the flange of the can bodies to which they are to be attached. 110

In testimony whereof, I affix my signature, in the presence of two witnesses.

IVAR F. WARME.
